EXPANSIBLE UNDERREAMER TRIP

Original Filed Jan. 3, 1928

UNITED STATES PATENT OFFICE

ROLAND CRUM, OF WHITTIER, CALIFORNIA, ASSIGNOR, BY MESNE ASSIGNMENTS, TO
JOHN GRANT, OF LOS ANGELES, CALIFORNIA

EXPANSIBLE UNDERREAMER TRIP

Application filed January 3, 1928, Serial No. 244,126. Renewed August 18, 1931.

This invention relates to a trip mechanism for holding two longitudinally movable members against movement and actuatable by fluid pressure to release said members.

In tools for well drilling operation having work performing members expansible and collapsible by manipulation of the tool, it is desirable to set and maintain the tool parts in collapsed position and to release them at will. Thus, it is desirable to run such a tool into the bore hole, and, when the position for expansion has been attained, to release the expansible parts. This invention appertains to a tool wherein fluid is applied to the tool and pressure is caused to be exerted by the fluid, there being a trip mechanism arranged to be operated by fluid pressure so as to release the expansible parts and cause expansion of the tool parts. A specific application of the invention is embodied in an expansible underreamer having cutters for expansion and collapse. The present invention contemplates use in a tool provided with a body having expansible work performing members, such as cutters, and an expander movable in the body in an axial direction to cause expansion and collapse of the cutters, means for urging the expander into position for expanding said cutters, and a novel trip mechanism to restrain the expander from moving into cutter expanding position and operable by circulation fluid, such as the slush employed in rotary hydraulic drilling. An underreamer embodying these features is disclosed herein.

The objects of this invention are first, to provide a tool of the character described with a catch to retain the parts in collapsed condition and actuatable by fluid pressure to release the same for expansion; second, to provide a tool of the character described with trip mechanism having a valve slidably plunger for holding and releasing the catch; and third, to provide details of structure, whereby a simple, durable tool, easily assembled and easy of manipulation is obtained.

An embodiment of this invention is disclosed in the accompanying drawings in which:

Fig. 1 is a longitudinal section through an

expansible underreamer in collapsed condition, parts being broken out to contract the view; Fig. 2 is a longitudinal view of a fragment of the tool showing the parts in expanded position; Fig. 3 is a longitudinal section through the spring sleeve; Fig. 4 is a section as seen on the line 4—4 of Fig. 1; and Fig. 5 is a section as seen on the line 5—5 of Fig. 1.

Referring with more particularity to the drawings a body is indicated by A, and mounted in the body so as to be longitudinally movable with respect thereto is an expander B. The trip mechanism is indicated generally by C.

The body includes a cutter supporting section 6 longitudinally slotted at 7 to accommodate the cutter assemblies or work performing members. The lower end has a stem 8 to which a fish-tail bit may be connected by means well known in the art and not shown herein. The upper end of the body is externally reduced in diameter and threaded to receive a spring sleeve 9. The latter forms a part of the body and is provided with an internal shoulder 10 adjacent the top. The upper edge of the spring sleeve is rounded. Key-ways 12 extend along the spring sleeve between the edge 11 and the shoulder 10.

The expander includes a wedge head 14 provided with mortises 15 for alignment with slots 7 in the body. It has a bore 16 extending therethrough and a threaded box at its upper end with which is engaged a pin 17. The pin has a flanged head 18 and a bore forming a continuation of the bore 16. Mounted over the pin is an intermediate portion 19. A socket 20 slidably receives the head 18 of the pin, and a bushing 21 serves to hold the head in position with a packing ring, preferably of rubber and indicated by 22 about the head. A wear ring 23 is disposed between the bushing and the expander head. This provides for a swivel connection between the head and the remaining portion of the expander. A socket is provided in the upper portion of the intermediate member and is internally threaded to receive a pin. An external limiting shoulder 24 is provided on the upper end of the intermediate member 19 for engaging

the upper end of the cutter body 6 and to serve as an abutment for a compression spring. A shank portion 25 of tubular form has a threaded pin end 13 engaged in the box 5 at the upper end of intermediate member 19 and at the other end a tapered threaded pin end 26. An opening 27 in the shank serves for communication between a catch key cavity 28 on the outer face of the shank and the bore 10 of the shank. This cavity is undercut at the upper end as indicated by 29. Radially projecting keys 30 on the shank are engaged with the key-ways 12 in the spring sleeve. Surrounding the shank and within the spring 15 sleeve is a compression spring 31 tending to retract the expander within the body. Mounted on the upper end of the shank is a sub 32 having a threaded pin 33 for connection to a drill pipe. A bore is provided in 20 the shank forming a continuation of the bore in the stem shank.

Mounted within the cavity 28 is a catch key 34 having a shoulder 35 conforming its shape to the rounded edge of the spring sleeve 25 so that it may engage thereagainst and ride thereover. Extending from the inner side of the catch key and through the opening 27 is a finger 36. Mounted so as to be reciprocable within the bore of the shank is a plunger slide 37 having a bore therein and an annular recess 38 for the finger 36 on the catch. The upper end of the plunger is formed with a valve seat for a valve plug 39. A stem 40 is secured to the plug and passes through a 30 guide of spider form as indicated by 41, which guide is secured in the bore of the stem. The guide has a hub 42 which may be engaged by abutment nuts 43 mounted on stem 45.

40 The trip mechanism is such that the slide plunger may have a limited downward reciprocable movement with the valve plug resting thereon and closing the bore. However, after the abutment nuts engage the hub 45 of the guide, the valve will be unseated by further movement of the plunger.

45 The cutter assemblies each comprise a block 44 mounted by a pivot pin 45 in a slot of the body. These blocks have tenons which engage the mortises 15 in the wedge head. An upper block 46 is engaged with the head by a tenon disposed in a mortise 15. A set of rollers 47 are journaled between the upper and lower blocks. The cutter assemblies are 55 such that upon the wedge being positioned as shown in Fig. 1, they will be retracted or collapsed, and when the wedge is in the position shown as in Fig. 2 they will be protracted or expanded. The spring 31 urges 60 the expander into its cutter expanding position.

65 The tool is collapsed by withdrawing the stem and moving the plunger slide into its upper position, the key 37 being in its outer position with its shoulder 35 resting against

the upper face of the spring sleeve. The finger 36 will rest against the slide and the valve 39 will close the bore of the plunger. The tool is then lowered to the position desired for expansion of the tool. Circulation 70 is inaugurated causing pressure downwardly upon the plunger. The plunger will be moved downwardly the valve plug 39 following it closing the bore. Finally the recess 38 in the plunger slide registers with the finger 75 36 and the pressure of the spring 31 on the stem urging it inwardly will cause the key to ride over the edge 11 and clear the latter. The spring is then free to force the expander 80 into expanding position. Before the plunger reaches its final position, abutment nuts 43 will have engaged hub 42 and unseated the valve 39 so as to keep the circulation passage open. Rotation of the stem for drilling is then begun. The rotational effort is transmitted 85 from the expander to the body through the keys 30 and the key-ways 12. Thus, there will be no tension upon the wedge head and there will be no tendency to bind the cutter mechanism in the slot. 90

The subject matter claimed in this case is subsidiary to that claimed in copending application Ser. No. 244,125 filed on even date herewith; and is companion to that of copending application Ser. No. 244,127 filed on 95 the same date. Insofar as generic claims are made covering the specific subject-matter of this and the last mentioned application, the claims thereto are carried in the first mentioned application. The claimed subject 100 matter of this application is limited to the trip here shown; the second mentioned application is limited in claimed subject-matter to an improvement on the first distinct from the improvement of this case. 105

What I claim is:—

1. A tool of the character described comprising a body and a member longitudinally urgeable in relation thereto, said member having a bore for fluid extending thereinto, a catch mounted to restrain said member against movement in the urged direction, and a valved plunger slide for retaining said catch in restraining position reciprocable in said bore by fluid pressure to a position releasing said catch, and means to unseat said valve when disposed in releasing position. 110

2. A tool of the character described comprising a body and a member longitudinally urgeable in relation thereto, said member having a bore for fluid extending thereinto, a catch mounted to restrain said member against movement in the urged direction, a hollow plunger slide for retaining said catch in restraining position and reciprocable in said bore by fluid pressure to a position releasing said catch, a valve for closing the bore of and reciprocable with said slide, and means to limit reciprocation of said valve to 120 125 130

unseat the latter at the releasing position of said slide.

3. A tool of the character described comprising a body and a member longitudinally urgeable in relation thereto, said member having a bore for fluid extending therethrough, a catch mounted to restrain said member against movement in the urged direction, a hollow plunger slide for retaining said catch in restraining position and reciprocable in said bore by fluid pressure to a position releasing said catch, a reciprocable valve controlling the flow of fluid through the bore of said slide and provided with a stem, said valve being reciprocable with said slide in position closing the valve port, and a limiting means for said valve to engage said stem and unseat said valve at the releasing position of said slide.

4. A tool of the character described comprising a body and a longitudinally urgeable member therein having a bore extending therethrough for fluid; a catch mounted on said member to engage the surface on said body and restrain said member against movement in the urged direction; and a trip mechanism including a slide for retaining said catch in restraining position being operable by pressure of fluid in said bore to release said catch.

5. A tool of the character described comprising a body and a longitudinally urgeable member therein having a bore extending therethrough for fluid; a catch mounted on said member to engage the surface of said body and restrain said member against movement in the urged direction; and a trip mechanism including a slide for retaining said catch in restraining position reciprocably disposed in the bore of said urgeable member and movable by pressure of fluid therein to release said catch.

6. A tool of the character described comprising a body and a longitudinally urgeable member therein having a bore extending therethrough for fluid; a catch mounted on said member to engage the surface on said body and restrain said member against movement in the urged direction; and a trip mechanism including a valved plunger slide for retaining said catch in restraining position reciprocable in said bore by fluid pressure to a position opening the valve and releasing said catch.

7. A tool of the character described comprising a body and a longitudinally urgeable member therein having a bore extending therethrough for fluid; a catch mounted on said member to engage a surface on said body and restrain said member against movement in the urged direction; and a trip mechanism including a valved plunger slide for retaining said catch in restraining position reciprocable in said body by fluid pressure to a position releasing said catch, and means to un-

seat said valve when disposed in releasing position.

8. A tool of the character described comprising a body and a longitudinally urgeable member therein having a bore extending therethrough for fluid; a catch mounted on said member to engage a surface on said body and restrain said member against movement in the urged direction; and a trip mechanism including a hollow plunger slide for retaining said catch in restraining position and reciprocable in said bore by fluid pressure to a position releasing said catch, a valve for closing the bore of and reciprocable with said slide, and means to limit reciprocation of said valve to unseat the latter at the releasing position of said slide.

9. A tool of the character described comprising a body and a longitudinally urgeable member therein having a bore extending therethrough for fluid; a catch mounted on said member to engage a surface on said body and restrain said member against movement in the urged direction; a trip mechanism including a hollow plunger slide for retaining said catch in restraining position and reciprocable in said bore by fluid pressure to a position releasing said catch, a reciprocable valve controlling the flow of fluid through the bore of said slide and provided with a stem, said valve being reciprocable with said slide into position closing the valve port, and limiting means for said valve to engage said stem and unseat said valve at the releasing position of said slide.

10. A tool of the character described comprising a body having a longitudinally extending bore, a longitudinally urgeable member movable in said bore having a bore extending therethrough for passage of fluid, there being a longitudinally extending keyway in said body; a catch key mounted in said way with one end supported by an end wall of said way and the other end disposed to engage an opposing surface on said body when in projected position so as to restrain said member against movement in the urged direction and to release said key when in retracted position so as to clear said surface and release said member; and a slide for retaining said key in restraining position being operable by pressure of fluid in the bore of said members to release said key.

11. A tool of the character described comprising a body having a longitudinally extending bore, a longitudinally urgeable member movable in said bore having a bore extending therethrough for passage of fluid, there being a longitudinally extending keyway in said member, a catch key mounted in said way with one end supported by an end wall of said way and the other end disposed to engage an opposing surface on said body when in projected position so as to restrain said member against movement in the urged

direction and to release said key when in retracted position so as to clear said surface and release said member; and a slide for retaining said catch in restraining position 5 reciprocably disposed in said bore and movable by pressure of fluid therein to release said catch.

12. A tool of the character described comprising a body having a longitudinally extending bore, a longitudinally urgeable member movable in said bore having a bore extending therethrough for passage of fluid, there being a longitudinally extending key-way in said member, a catch key mounted in 10 said way with one end supported by an end wall of said way and the other end disposed to engage an opposing surface on said body when in projected position so as to restrain said member against movement in the urged 15 direction and to release said key when in retracted position whereby to clear said surface and release said member; and a valved plunger slide for retaining said catch in restraining position reciprocable in said bore 20 by fluid pressure to a position opening the valve and releasing said catch.

13. A tool of the character described comprising a body having a longitudinally extending bore, a longitudinally urgeable member movable in said bore having a bore extending therethrough for passage of fluid, there being a longitudinally extending key-way in said member, a catch key mounted in 25 said way with one end supported by an end wall of said way and the other end disposed to engage an opposing surface on said body when in projected position so as to restrain said member against movement in the urged direction and to release said key when in 30 retracted position whereby to clear said surface and release said member; a valved plunger slide for retaining said catch in restraining position reciprocable in said bore 35 by fluid pressure to a position releasing said catch, and means to unseat said valve when disposed in releasing position.

14. A tool of the character described comprising a body having a longitudinally extending bore, a longitudinally urgeable member movable in said bore having a bore extending therethrough for passage of fluid, there being a longitudinally extending key-way in 40 said member, a catch key mounted in said way with one end supported by an end wall of said way and the other end disposed to engage an opposing surface in said body when in projected position so as to restrain said members against movement in the urged direction and to release said key when in retracted position 45 whereby to clear said surface and release said member, a hollow plunger slide for retaining said catch in restraining position and reciprocable in said bore by fluid pressure to a position releasing said catch, a valve for closing the bore of and reciprocable with said

slide, and means to limit reciprocation of said valve to unseat the latter and to release the position of said slide.

15. A tool of the character described comprising a body having a longitudinally extending bore, a longitudinally urgeable member movable in said bore having a bore extending therethrough for passage of fluid, there being a longitudinally extending key-way in said member; a catch key mounted in 70 said way with one end supported by an end wall of said wall and the other end disposed to engage an opposing surface of said body when in projected position so as to restrain said members against movement in the urged direction and to release said key when in retracted position whereby to clear said surface and release said member, a hollow plunger slide for retaining said catch in restraining position and reciprocable in said bore by 75 fluid pressure to a position releasing said catch, a reciprocable valve controlling the flow of fluid through the bore of said slide and provided with a stem, said valve being reciprocable with said slide into position closing the valve port, and limiting means for 80 said valve to engage said stem and unseat said valve at the releasing position of said slide.

16. A tool of the character described comprising a tubular body portion, a hollow stem 95 longitudinally urgeable into the bore of said body and projectable beyond the same, means for urging said stem into said body, there being an outer shoulder at the end of said body and a cavity in said stem, a catch key accommodated in said cavity with an end projectable to engage said shoulder when in outer position and to clear said shoulder when in inner position, a finger on said key extendible 100 through an opening communicating with the bore of said stem; a plunger slide for retaining said catch in restraining position reciprocable in the bore of said stem by fluid pressure, said finger being engageable with said slide to retain said catch in restraining position, there being a cavity in said plunger to 105 receive said finger and release said catch, and a valve in said plunger closed at the restraining position of said plunger and open at the releasing position.

17. A tool of the character described comprising a tubular body portion, a hollow stem longitudinally urgeable into the bore of said body and projectable beyond the same, means for urging said stem into said body, there being an outer shoulder at the end of said body and a cavity in said stem, a catch key accommodated in said cavity with one end supported on an end wall of said cavity and the other end transversely projectable to engage said shoulder when in outer position and to clear said shoulder when in inner position, a finger on said key extending through an opening communicating with the bore of said stem; a plunger slide for retaining said catch in re- 115 120 125 130

straining position reciprocable in the bore of said stem by fluid pressure, said finger being engageable with said slide to retain said catch in restraining position, there being a cavity 5 in said plunger to receive said finger and release said catch, and a valve in said plunger closed at the restraining position of said plunger and means to open said valve at the releasing position.

10 In witness that I claim the foregoing I have hereunto subscribed my name this 5th day of December, 1927.
